UNITED STATES PATENT OFFICE

159,807

COMBINED RAZOR AND BLADE HOLDER

Richard D. Hanson, Allwood, Clifton, N. J.

Application November 27, 1948, Serial No. 149,853

Term of patent 3½ years

(Cl. D4—3)

To all whom it may concern:

Be it known that I, Richard D. Hanson, a citizen of the United States of America, residing at Allwood (Clifton), in the county of Passaic, State of New Jersey, have invented a new, original, and ornamental Design for a Combined Razor and Blade Holder, of which the following is a specification, reference being had to the accompanying drawing, forming part hereof.

In the drawing:

Figure 1 is a front elevational view of a combined razor and blade holder, showing my new design;

Figure 2 is a rear elevational view;

Figure 3 is a side elevational view; and,
Figure 4 is a top plan view of Figure 2.

I claim:

The ornamental design for a combined razor and blade holder, as shown.

RICHARD D. HANSON.
